BISTABLE TRIGGER CIRCUIT

Johann O. Kleinschmidt, Korntal, Wurttemberg, Germany, assignor to International Standard Electric Corporation, New York, N.Y., a corporation of Delaware

Filed Nov. 6, 1959, Ser. No. 851,387

Claims priority, application Germany Nov. 7, 1958
3 Claims. (Cl. 307—88)

The present invention relates to a bistable trigger circuit comprising two operating circuits, of which one is conductive while the other is non-conductive, and in particular to a transistorized flip-flop circuit. Such types of trigger circuits are well known from the fields of computing machines. However, they bear the disadvantage that in the event of an absence of the operating voltages, the informations which are stored in the flip-flop will go astray. For this reason, in the case of data-processing systems, in addition to the flip-flop storage circuits, such as counting chains, shifting registers, and the like, permanent storage devices are provided permitting the transference of a defined initial condition to the flip-flop circuits. In cases where such types of permanent storage devices are not already available, control leads or lines are provided for enabling an erasing of the flip-flop storage, so that a defined initial condition can be achieved. In this way, however, the disadvantage that the last stored information will go astray cannot be avoided.

The present invention is based on the problem of improving the afore-mentioned flip-flop circuits with as little as possible additional investment in circuitry, in such a way that, upon reinsertion of the operating voltage, they will reassume the original circuit condition, so that it will no longer be necessary to store the last stored information into a special permanent storage device prior to the disconnection of the operating voltage, and to cause this permanent storage device to perform the resetting of the flip-flop circuit in accordance with the stored information subsequently to the insertion of the operating voltage.

According to the invention, this problem is solved by inserting into each of the two operating circuits one of two oppositely wound windings with a common ferromagnetic core having an approximately rectangular hysteresis loop, in such a way that the information stored in the trigger circuit upon disconnection of the operating voltage will remain in the core, and upon reinsertion of the operating voltage, the trigger circuit will reassume that particular operating condition corresponding to the information as stored in the core. A trigger circuit constructed in this way according to the invention, bears the advantage that the storing and reading processes which were hitherto necessary for avoiding losses of information are avoided.

The invention is illustrated in the accompanying drawings, in which:

FIG. 1 is a schematic diagram of a transistorized flip-flop circuit embodying the invention; and

FIG. 2 is a schematic diagram of a modified form of the flip-flop circuit shown in FIG. 1.

Referring to FIG. 1, a transistorized flip-flop circuit is shown comprising the transistors T_1 and T_2 , as well as their respective operating resistors R_1 and R_2 . The base electrodes of the transistors T_2 and T_1 are connected respectively via the resistors R_5 and R_6 to a positive potential $+V_2$, and respectively via RC-circuits C_1R_4 and C_2R_3 with the operating resistors R_2 and R_1 . A winding W_1 is connected between the collector of transistor T_1 and the operating resistor R_1 , and a winding W_2 is connected between the collector of transistor T_2 and its operating resistor R_2 . These windings are wound in opposite sense on

2

one common core K , consisting of ferromagnetic material. The windings are so dimensioned that whichever circuit is conductive will magnetize the core. If, for example, the transistor T_1 is conductive or unblocked, then a current will be flowing from ground OV, via the emitter-collector path of T_1 , via the winding of W_1 , and via the operating resistor R_1 , towards the line of the negative operating potential $-V_1$. The current flowing in the winding W_1 will enforce a certain condition of saturation in the core K . The voltage drop across R_1 will cause a relatively small current to flow across the voltage-dividing circuit consisting of the voltage-dividing resistors R_3 and R_5 , so that the base electrode on the transistor T_2 will remain positively biased. Accordingly, the transistor T_2 will remain blocked. This operating condition will remain until, for example, the circuit arrangement is triggered into the other condition by the application of a negative pulse to the base electrode of the transistor T_2 . If T_2 is controlled in such a way that a current will now be flowing via the emitter-collector path of T_2 , via the winding W_2 and the operating resistor R_2 , then by the voltage drop across R_2 , which is immediately transferred via the coupling capacitor C_1 to the base of the transistor T_1 , the transistor T_1 will be blocked. During this relaxation or triggering process, as soon as the current in the winding W_2 sufficiently predominates over the current flowing in the winding W_1 , the core K will be resaturated in the other sense. If the operating voltage is now disconnected, then the condition of remanence of the core will indicate in what operating condition the trigger circuit had been prior to the disconnection of the operating voltage. Upon reconnecting or reinserting the operating voltage, the trigger circuit is at first in an unstable condition, that is, neither of the two circuits is conducting its complete or full current. With respect to the circuit which had been blocked prior to the disconnection, the core will represent a high impedance, as soon as the current in this circuit and in the core winding produces a field tending to resaturate the core, in other words, is trying to shift the core from the saturation condition into the area of a high permeability. With respect to the other circuit, however, the core represents a small impedance, because in this circuit no current flow is necessary to further drive the core into the saturation condition. This asymmetry of the trigger circuit forces it to return to the condition which is assumed prior to the disconnection.

A particularly advantageous amplification of this effect can be achieved by providing two further windings which are inserted into the connections between the control electrodes and the lead-in conductors of the control lines. The arrangement is such that the circuit which tends to resaturate the core upon insertion or connection of the operating voltage is blocked by the voltage as induced in the additional winding. In the embodiment of FIG. 2, these additional windings are denoted by the references W_3 and W_4 . The base electrode of the transistor T_1 is its control electrode and is connected via the winding W_3 with the control line S_1 , and the base electrode of the transistor T_2 is connected via the winding W_4 with the control line S_2 .

If, for example, prior to the disconnection of the operating voltage, the transistor T_1 had been conductive or unblocked, and the operating voltage is reinserted again, then the current flow which is effected through the winding W_1 is no longer capable of resaturating the core. However, if in the unstable initial condition, the transistor T_2 has a greater conductivity at first, the current via the winding W_2 could initiate a resaturation. In the course of this, however, a blocking signal with respect to the transistor T_2 is induced in the control winding W_4 . At

the same time, an opposite signal adapted to trigger the transistor T_1 into the conductive or unblocked condition is induced in the winding W_3 .

The described embodiments relate to transistorized flip-flop circuits. The invention, however, can also be advantageously applied to other circuits, such as tube circuits.

While I have described above the principles of my invention in connection with specific apparatus, it is to be clearly understood that this description is made only by way of example and not as a limitation to the scope of my invention as set forth in the objects thereof and in the accompanying claims.

What is claimed is:

1. A bistable trigger circuit comprising two transistors connected to form a flip-flop circuit, said circuit comprising a ferro-magnetic core with an approximately rectangular hysteresis loop, a pair of oppositely wound windings on said core, means connecting one of said windings to a first electrode of one of said transistors, means connecting the other of said windings to a corresponding first electrode of the other of said transistors, a source of potential, a pair of operating resistors connected respectively between the other ends of said windings and said source, and separate means connecting each junction of a winding and a resistor to a second electrode of the

transistor whose first electrode is not connected to said winding, whereby, upon disconnecting said source, the information as stored in said trigger circuit will remain in said core, and upon reconnecting said source, said trigger circuit will resume that particular operating condition that corresponds to the information as stored in said core.

2. A bistable trigger circuit, as claimed in claim 1, in which the two windings on the core are connected respectively between the collectors and the operating resistors of the transistors.

3. A bistable trigger circuit, as claimed in claim 2, further comprising a control lead for each transistor, and in which the ferro-magnetic core is provided with two further windings which are respectively inserted between the bases and the control leads of two transistors.
